UNITED STATES PATENT OFFICE

JAMES CAMROD LEDBETTER, OF JACKSON HEIGHTS, NEW YORK, ASSIGNOR TO THE PROSPERITY COMPANY, INC., OF SYRACUSE, NEW YORK, A CORPORATION OF NEW YORK

GARMENT OR IRONING PRESS

Application filed October 27, 1930. Serial No. 491,383.

This invention relates to garment or ironing presses for use in laundries, valet shops, homes and the like.

An object is to produce a garment or ironing press particularly adapted for use in homes, storerooms and the like, where occasionally it is desired to do pressing and ironing work by mechanical means and upon completion of such work to easily and quickly 10 move the pressing machine out of the way and store it in a space as small as possible. One of the objects of my invention is to produce a garment or ironing press for the 15 purposes above set forth which, by reason of the construction, arrangement and combination of the various parts thereof, will be lighter in weight and more compact than the ordinary industrial press and at the same time not materially reduce the capacity or 20 usefulness thereof.

Another object is to produce a garment or ironing press of the class described in which pedal or treadle operated means for actuating coacting press jaws is disposed within an 25 enclosed, compact, pedestal-like frame or housing which not only serves as a protecting guard for the moving parts of the machine but also imparts thereto a pleasing and attractive appearance.

A further object is to produce a garment or ironing press of the class described comprising boiler means mounted integral with the press head and its actuating arm and adapted to supply steam for heating the press head 30 and for moistening the material to be pressed in combination with press head actuating means which is largely concealed within the frame of the machine.

A further object is to produce a foot power 40 garment or ironing press having all the movable links and levers, which are provided for opening and closing the coacting press jaws, disposed within, or in a substantially axial prolongation of a symmetrical pedestal-like 45 frame or support and to make the frame or support of such size and construction that when the press is standing upon the floor, in operative position, the frame makes contact with the surface of the floor over an area of sufficient size to frictionally anchor the press

to the floor, so to speak, and to prevent it from creeping during the operation thereof; and moreover to construct, within the press frame or support, foot power actuated means for projecting and retracting at will, a set of 55 casters adapted to lift the press bodily from the floor so as to enable it to be moved from place to place when not in use and have both of these foot power mechanisms, that is, the mechanism for opening and closing the press and for operating the casters, so constructed and correlated that the pedals for operating them will project from the base of the frame or support in close proximity to one another and be adapted to actuate their respective 60 mechanisms by applying their actuating forces at points located substantially in the vertical axis of the machine or at points disposed equidistant therefrom.

Further objects and advantages of my present invention will become apparent from the following specification and the appended claims in which I define the same, or will be specifically referred to hereinafter.

My invention is illustrated in the accompanying drawings, in which:

Figure 1 is a front elevational view of my garment or ironing press showing the press jaws in closed or pressing position; and the pedestal-like frame or support upon which said press jaws are mounted and also the exterior arrangement of the pedal or treadle means for operating the press jaws and elevating the press from the floor by means of a caster actuating mechanism when it is desired to move the press from place to place.

Figure 2 is a cross-sectional view of the lower portion of the press pedestal or frame showing a portion of the press head actuating means in operative or closed press position and a set of casters and the operating mechanism therefor, which is adapted to raise the press from the floor when it is desired to roll it about from place to place.

Figure 3 is a cross-sectional view of the lower portion of the pedestal or frame, similar to Figure 2, except that it shows a portion of the press head actuating means in inoperative or open press position and the caster operating

mechanism in its operative position with the casters projecting below the frame.

Figure 4 is a cross-sectional plan view of the base portion of the pedestal or frame, 5 which I shall call a housing, and is drawn as seen from line 4-4 of Figure 3 and shows a plan view of the caster operating means including the actuating treadle.

Figure 5 is a left hand side elevational view 10 of my press, partly in section, showing in detail the construction of the hollow pedestal-like frame or support, like that shown in Figure 1, and the manner in which the parts of the treadle actuating mechanism is disposed therein, and also modified forms of 15 press head and caster actuating means.

Figures 6 and 7 are front and side elevational views, respectively, of the lower portion of the pedestal or frame, shown in Figure 5.

Figure 8 is an assembled detail view of the pin and slot connection between the caster actuating levers shown in Figure 5.

Referring now to the accompanying drawings it will be seen that my garment or ironing press is supported by or mounted on a frame, which I designate generally, by the numeral 10. The frame 10 is of pedestal formation and comprises a base or housing 11 provided with a flange 12 and a sill 13 formed on the upper central portion thereof and adapted to receive and furnish support for a hollow tubular standard 14 open at both ends. A horizontal support 15 is mounted on the upper end of the standard 14 by means of a flange and socket connection 16; the upper end of the standard 14 being designated by the numeral 17 and shown in dotted lines in Figure 5. When the parts 11, 14 and 15, of the pedestal or frame 10, are assembled they are rigidly secured together, by any suitable means, whereby they form a rigid, hollow support for the press. An important feature of a press pedestal of this type is to make the portion of the lower edge of the housing 11, which is adapted to rest upon the floor, flat; and of an area to afford sufficient frictional resistance to prevent the press from creeping when it is being operated with the press standing upon the floor.

The support 15 is provided with an upright bracket 20 terminating at its upper end in oppositely extending ears 21, 21 (see Figure 1) which are adapted to support a buck 22, rigidly secured thereto. The rear end of the support 15 is constructed in the form of an upright bracket 23 having a pair of vertically disposed spaced arms 24, 24. A steam boiler 25 is pivotally mounted on the arms 24, 24 by means of trunnions 26, 26 which are secured to either side of the boiler at points opposite the center of gravity of the boiler, whereby the boiler may be easily and freely rocked back and forth on the trunnions 26, 26, in the arm 24, 24 of the bracket 23. A

press head 27, disposed above the buck 2, is secured to the forwardly extending ends of a pair of arms 28, 28, having their rearwardly extending ends spaced apart, so as to span the boiler 25. The rearwardly extending ends of the arms 28, 28 are rigidly secured at the sides of the boiler 25 to the trunnions 26, 26, respectively. A steam supply pipe 29 and a condensation return pipe 30 are rigidly connected between the boiler 25 and the press head 27. The boiler 25 is adapted to be heated by means of an electrical resistance, not shown, although the terminal connections 31, illustrated in Figure 5, are brought to the exterior of the boiler near the base thereof and adapted for the attachment of electric current supply lines.

It will be seen that the structure just described, comprising the boiler 25, press head 27, arms 28, 28 and pipes 29 and 30 are rigidly assembled, as a unit, and adapted to rock about the arms 24, 24 on the trunnions 26, 26 whereby to open and close the coacting press jaws 22, 27; or in other words, to adapt the press head 27 to press and iron the work spread upon the buck 22. I provide a handle 32 mounted between the front ends of the arms 28, 28 to be used in conjunction with other mechanisms, to be hereinafter described, for opening and closing the press and applying pressure to the buck and press during the pressing operation.

I now provide for the employment of foot power and spring means for operating the press head to and from the buck, see Figures 1, 2 and 3, in the form of a pedal or treadle 35 keyed to a shaft 36 extending longitudinally across the housing 11 from side to side, said shaft being revolvably mounted in bearings 37 in the housing. The treadle 35 is adapted to actuate a lever 38, pivotally mounted on the housing 11 in a bearing 39, by means of toggle links 40 and 41 which are connected between the end of the lever 38, remote from the bearing 39, and the shaft 36, the toggle link 40 being rigidly secured to the shaft 36. A link 42, disposed within the hollow standard 14, is connected by means of a pin 43 to the lever 38 at a point between the ends thereof; said point of connection being substantially in alignment with the vertical axis of the press frame 10 which I have described above.

The other end of the link 42 terminates in the form of a yoke or stirrup 44 and the ends thereof are pivotally secured to the arms 28, 28 respectively, by means of pins 45 located between the boiler and press head. The lever 38 is urged upwardly by a tension spring 46 connected thereto and anchored to a fixed support 47 located on the inside of the hollow standard 14, see Figures 2 and 3. A pedal or treadle 48 is rigidly secured to the end of the shaft 36, remote from the treadle 35, above described, so as to project from the op-

posite side of the shaft 36, that is, at an angle of approximately 180° behind the treadle 35. The purpose of locating the pedal 48 in this manner will be presently described.

5 If pressure is applied to the treadle 35, when it occupies the position shown in Figure 3, it will move downwardly and rotate the shaft 36, and the link 40 keyed thereto, in a clockwise direction and move the lever 38 downwardly by means of the link 41 connected between link 40 and the end of the lever 38. When the lever 38 is moved downwardly it actuates the link 42 and by virtue of the connection between the upper end of the link 42, through the intermediary of the yoke 44, with the arm 28, the press head and boiler unit, above described, is rocked about the trunnions 26, 26 to close the press head 27 against the buck 22. When the treadle 35 is moved downwardly to close the press head the toggle links 40, 41, are locked in alignment, see Figure 2, with the result that the head 27 is pressed upon the buck 22 and is adapted to remain so as long as desired. 25 It will be apparent, by reference to Figure 1, that when the treadle 35 is moved downwardly the treadle 48 will be moved upwardly because as above described it is keyed to the shaft 36 and extends therefrom in a direction opposite to the treadle 35. After the pressing operation is completed and it is desired to open the press to remove the work from the buck the operator does so by pressing the treadle 48 and rocking the shaft 36 in a counter-clockwise direction with the result that the toggle 40, 41 is broken and the press head lifted to open press position by means of the spring 46. It will now be understood that the press may 35 be opened and closed by treadle actuated means independently of the handle 32 on the arms 28, 28 although the handle may be found useful as an auxiliary means of closing the press.

45 Mounted on the front part of the support 15 around the bracket 20 and under the buck 22, is a table 49 having an upwardly extending rear portion or guard 50 disposed between the press jaws and the operative parts 50 of the press to the rear thereof to prevent materials which are being worked upon from coming in contact with these moving parts and being damaged.

55 Referring now to Figures 2, 3 and 4 it will be seen that I provide means for projecting and retracting a set of casters for raising the press from the floor when it is desired to move it from place to place or set the press securely on the floor at the location where it is to be used. My caster operating means comprises a pedal or treadle 55 mounted on a bar 56 having the ends thereof bent backwardly, with reference to the treadle, to form a pair of parallel spaced levers 57 and 58, said lever and pedal struc-

ture being pivotally secured by means of hinge pins 59 and 60 to the inside of the housing 11. A second set of levers 61 and 62 are pivotally secured by hinge pins 63 and 64 to the inside of the housing 11 at points 70 opposite the pins 59 and 60, respectively, and have their other ends connected to the levers 57 and 58 by pin and slot connections 65 and 66. Casters 67 are revolvably mounted in sockets 68 formed in the levers 57, 58, 61 and 62 near the pins 59, 60, 63 and 64 which connect one end of each of said levers to the inside of the housing 11 as aforesaid.

To raise the press from the floor and support it by means of the casters 67 instead 80 of the bottom of the pedestal or frame 10, the operator presses the treadle 55 which rotates the levers 57, 58, 61 and 62 slightly about their hinge pins 59, 60, 63 and 64 whereby the casters 67 carried thereby are 85 thrust from beneath the housing 11 with the result that the press as a whole is elevated from the floor and supported by the casters so that it is adapted to be rolled freely about the floor. The casters 67 are held in their 90 depressed position by means of a spring-actuated snap-hook 69 which engages the treadle 55 and when it is desired to raise the casters to lower the press to the floor the snap-hook 69 may be released by depressing 95 a pedal 70 formed integral therewith, and when the treadle 55 is released the hook 69 will return to its normal position against a pin 71 to which it is constantly urged by a leaf spring 72. 100

Referring now to Figures 5, 6 and 7 I show a modified form of pedal actuating means for operating the press head 27 by means of the link 42 and its associated parts. This modification provides for a centrally disposed foot pedal 75 and lever 76 pivotally mounted on the rear wall of the housing 11 by means of a pin 77, the housing having a slot 78 in the front wall through which the lever 76 may be inserted at the time the machine is assembled and thereafter actuated.

The link 42 is connected to lever 76 by means of a pin 79 intermediate its ends and positioned substantially in line with the vertical axis of the frame 10. Casters 80, 81, 82 and 83, only the first two of which are shown in Figure 5, are mounted in bearing blocks 84 formed in the four corners of the housing, respectively. These casters are provided with cylindrical shank portions 85 slightly longer than the thickness of the bearing blocks 84 and provided with rounded heads 86 and are adapted to move freely up and down in the bearing blocks, their movement being limited by a flange 87 secured to the lower end of the 115 shank and the head 86 on the top of the shank.

The casters are operated in pairs (see 80 and 81, Figure 5) by means of a link 88 pivotally mounted on a pin 89 in the corner of the housing 11 at a point a little above, and in 130

the same vertical plane as the center of the mounting for the caster 80 and extends forwardly and upwardly, as seen in Figure 5, toward the front of the housing. A pedal 90 is mounted on the forward end of the link 88 by means of a stud 91 which operates in an arcuate slot 92 formed in the side wall of the housing 11. A link 93 is pivotally connected by means of a pin 94 to the front wall of the housing 11 at a point a little above and in the same vertical plane as the caster 81 and the other end of the link 93 is connected by means of a pin and slot connection 95 to the link 88, see Figure 8. The mechanism just described is adapted to thrust the casters 80 and 81 downwardly below the housing 11 when the pedal 90 is depressed, and when the pedal is raised the casters will again assume the position shown in Figure 5. It will be understood that a similar pedal 96 and an associated link mechanism, not shown, is provided on the other side of the press frame and that both pairs of casters 80-81, and 82-83, must be lowered by means of their respective link mechanisms to lift the press off the floor. In order to maintain the casters in their extended or operative positions, whereby the press may be moved at will about the floor, the pedal 90 is adapted to rock about the stud 91 by which it is secured to the link 88 whereby to effect an engagement between a hook 97 carried by the pedal 90 with a lug 98 on the side of the housing 11, see Figures 6 and 7.

While I have illustrated and described what now seems to be the preferred embodiment of my invention, I am aware that the structure shown is susceptible of modification and variation without departing from the essential features of my invention or exceeding the scope of the appended claims which particularly define the same.

What is claimed is:

1. A garment or ironing press comprising a frame of pedestal formation having a lower housing, and a hollow standard rising from the housing and open at each end, a horizontal support on the upper end of the hollow standard, an upright bracket on the front end of the horizontal support, a buck carried on the front bracket, another upright bracket on the rear of the horizontal support, boiler means carried on the rear bracket last-named, a press head, pipe connections between the boiler means and the press head, an arm having its front end attached to the press head and its rear end pivoted on the rear bracket; and operating means including a link within the hollow standard and having its upper end connected to the arm between its ends, and pedal means pivoted in the housing and connected to the link to draw down on the link to close the press head against the buck.

2. A garment or ironing press comprising a hollow frame, a horizontal support on the

upper end of the frame, an upright bracket on each end of the horizontal support, a buck on one bracket, a press head above the buck, boiler means pivotally carried on the other bracket to the rear of the buck and press head, rigid pipe connections leading from the boiler means to the press head, an arm having its rear end pivoted on the boiler pivot on the rear bracket and its other end reaching forwardly and attached to the press head; and operating means disposed within the frame and connected to the arm between the boiler and press head to actuate the press head by swinging the boiler, the pipe connections, and press head, as a unit.

3. A garment or ironing press comprising a frame including an upright hollow standard open at its upper end, bracket means carried on the upper end of the standard, said bracket means comprising a pair of spaced arms at the rear end thereof, a pivoted steam boiler mounted between the spaced arms on the rear of said bracket means and a buck mounted on the front thereof, a press head above the buck, and means connecting the press head and boiler whereby said press head and boiler are adapted to swing as a unit about the axis of the boiler pivot at the rear of the bracket, steam feed and return pipes rigidly connected to said boiler and press head, and operating means carried by the frame and extending out through the upper open end of the hollow standard and connected to the means connecting the press head and boiler and adapted to open and close the press.

4. A garment or ironing press comprising a frame of pedestal formation; said frame comprising a lower housing, and a hollow standard open at both ends and mounted thereon; a horizontal support on the upper end of the standard, and an upright bracket on each end of the horizontal support; a buck mounted on one bracket, and a press head above the buck; boiler means pivotally mounted on the other bracket to the rear of the buck and press head with the axis of said pivotal mounting being located on a horizontal line passing transversely of the machine through the center of gravity of the boiler, said axis being also located in the same plane as the pressing surface of the buck; in combination with an arm having its rear end pivoted on the boiler pivot and its forward end attached to the press head; and operating means connected to the arm for actuating the press head by swinging the boiler and press head as a unit about said pivot, said operating means extending through the hollow standard and having an operator-operated member extending from the lower housing.

In testimony whereof I affix my signature.
JAMES CAMROD LEDBETTER.
